PHOTOGRAPHIC CARD MOUNT

Filed March 15, 1938

INVENTOR
John E. Russell.

UNITED STATES PATENT OFFICE

111,795

DESIGN FOR A PHOTOGRAPHIC CARD MOUNT

John E. Russell, Scranton, Pa.

Application March 15, 1938, Serial No. 75,842

Term of patent 7 years

To all whom it may concern:

Be it known that I, John E. Russell, a citizen of the United States, residing at Scranton, in the county of Lackawanna and State of Pennsylvania, have invented a new, original, and ornamental Design for Photographic Card Mounts, of which the following is a specification, reference being had to the accompanying drawing, forming part thereof.

The figure is a front view of a photographic card mount showing my new design, the back of the mount being plain, the thickness being that of conventional cardboard and the essential features thereof being shown in full lines.

The mount has a central space to receive a photograph which is surrounded by an ornamental border consisting of the representations of jewels and flowers connected by chain links with a panel at the bottom of the border, in which is to be shown the name of a month of the year. The broken line showing of a birthstone and a birth-flower outside of the border are merely representative.

I claim:

The ornamental design for a photographic card mount, as shown and described.

JOHN E. RUSSELL.
